MACHINE FOR MAKING HANDLED
SHOPPING BAGS

Harford K. Steen, Newburgh, N. Y.

Application November 5, 1935, Serial No. 48,277

6 Claims. (Cl. 93—8)

My invention relates to a machine for making paper bags and the like, and more particularly to a machine for making what is known in the trade as "shopping bags" or "handled shopping bags", which have the handles attached thereto and which comprise a bag fabricated from kraft paper or other suitable material and to which cord handles made from twisted paper or the like are permanently attached during the process of forming the bag from the paper web.

The machine herein described and claimed is suitable for carrying out the steps of my method for making handled shopping bags such as are described in United States Patent No. 1,799,072, issued to me on March 31, 1931; and in my application for patent Serial No. 33,553, filed on July 27, 1935.

In the design of this bag making machine herewith shown, I have not included either a printing press for marking the web, or the partly made bags, or the bottom forming end of the machine, as these devices are well known in the art and may be readily attached or incorporated into the machine without invention, or my machine may be used without them as a separate machine, or as an attachment for the regular bag making machine, and I have therefore confined myself to making and attaching of the handles to the web, either from the stock paper roll or in the form of bag blanks which have already been cut from the stock roll into the proper lengths for the bags, and either printed or plain.

It is the present practice to make handled shopping bags by first making the bag and then attaching handles thereto by either wire staples, rivets passing through a card-board reinforcing pad under the turned in top or by threading the handle cord through holes formed in the bag, around the bottom or by gluing the handles between the bag and its turned in top, or the turned in top and a patch, all of which requires several different operations and handling that causes the finished product to be too high in cost.

To overcome these objections and to provide a bag that will be cheap, durable, efficient and pleasing in appearance, and yet have great strength in the attachment of the handles, I have devised a machine in which the web or bag blanks are formed into tubes in the usual way, but during this process the web has attached thereto a pair of suitable handles of cord or the like which are also formed in the same machine as well as the attaching patches; the tubes with the han-

dles attached either being finished in the same machine or in a separate machine as desired.

It has also been found that, in the present method of making handled shopping bags owing to the means employed for attaching the handles to the web, that when the bags are folded for baling for shipment, the handles, being superimposed one upon the other, will build up in thickness thus making a bulky bale and containing too few bags.

I have therefore provided against these conditions by so locating, forming and attaching the handles to the web or blank that when the same is tubed and folded the handles will nest one within the other thus presenting only one thickness of handle material which is about equal to the thickness of the folded bottom of the bag, so that the finished bags will bale in an even and compact manner.

I have also provided means whereby in place of attaching the handles to the web by long pieces of reinforcing material between which and the web the handles are held by an adhesive, I employ short pieces of reinforcing material in the form of patches, between which and the web, the handles are secured, thus creating a great saving in material and labor.

The machine is also designed so that bags of different widths can be made thereon, and the handles located with respect to the width of the web so that they will nest when the bag is folded.

This being accomplished by constructing the patch, handle making and attaching devices in a pair or two units, one of the units being stationary on the frame of the machine and the other having transverse adjustment so that the center distance between these two units can be varied to place the handles upon the web in the proper relation with the web and with each other in accordance with the width of the web, and it will be noted that in the detailed description of the machine I have only described one of these units as the other is a duplicate except that the handle is of a different width so that it will nest with the other handle.

The machine is also provided with means whereby the open end of the bag from which the handles project may be either of single thickness, or provided with an extending flange which may be folded inwardly and either pasted down or left loose.

The objects of the invention are to provide a machine automatic in its action, and in which both the patches and handles may be formed

from raw stock, assembled and attached to the web or bag blank during the process of forming the web into a bag.

Another object of the invention is to provide 5 a machine of this kind having few parts, adjustable for different sizes of bags within its limits, and having great speed of operation.

Another object of the invention is to provide 10 a device for forming handles from cord and attaching the formed handles to either a web or bag blanks, and which may be used as a separate machine, an attachment for a bag making machine or incorporated into a complete machine for making the entire bag.

15 With these and other objects in view, my invention consists in certain novel construction and combination of parts as will hereinafter be fully described and claimed and illustrated in the accompanying drawings, which form a part hereof 20 and in which like figures of reference refer to corresponding parts in all of the views, and it is understood that slight changes may be made without departing from the spirit of the invention.

25 In all of the drawings some of the parts are not shown, and other parts are shown in section to eliminate confusion, but the omitted parts will be found upon other of the views, also the main 30 drive of the machine and some of the driving or operating means employed for the different parts have been omitted as confusing, as these drives are all well known and comprise the usual gears, sprockets, chains, etc., used in this type of machine, and are all driven from the main drive.

35 Figure 1 shows a partial side elevation of a paper bag machine in which is embodied my invention, but the bag making mechanism is not shown as it forms no part of the invention, and is of well known type.

40 Figure 2 shows an enlarged partial side elevation partly in section of a portion of one of the units in which the patch material is formed into the patch, moistened, cut off and transferred.

45 Figure 3 is a front vertical sectional view of the patch moistener.

Figure 4 is a side elevation, partly in section of the handle forming device; patch and handle transfer and adhesive applicer for the web; the position of the several parts showing the handle 50 stock having been fed in to the former, but not cut off or formed.

Figure 5 is a similar view, but showing the position of the several parts after the handle has been cut off from the stock and formed, and is 55 being transferred to the web together with its patch.

Figure 6 shows a detail view of the adhesive applicator for placing the adhesive upon the web to receive the handles and patches.

60 Figure 7 indicates the manner in which the adhesive is located upon the web to receive the handle and patch.

Figure 8 is a partial top plan view of the handle feed, cut-off and forming mechanism, and shows 65 its relation to the patch and handle transfer device.

Figure 9 is a partial front view of the same, with some of the parts being shown in section.

Figure 10 is a detail view of the cord handle 70 feeding and cut-off devices.

Figure 11 shows the transfer roller with a patch and handle thereon ready to be applied to the pasted portions of the web.

75 Figure 12 shows a view of the finished folded bag.

Figure 13 shows a diagrammatic view of the web indicating the steps of manufacture for attaching the handles thereto.

Figure 14 shows a detail of the slit cutting knife and its roller.

Referring to Figure 1, I have shown one side of the main frame of a machine composed of the paper feeding end 10, and the finishing end 11, of a standard bag making machine, and I have extended apart these two ends 10 and 11 10 and mounted therebetween two side frames 12, which are formed near their upper edges with the transverse bearings for the braces 13 and 14, upon which are mounted the upper frames 15, which are four in number arranged in pairs to 15 form two units, one unit being permanently secured on the brace rods 13 and 14, while the other unit may be adjusted thereon to vary the center distance between the units for the proper spacing of the handles upon the web. 20

The supply or stock roll of bag paper 16, is mounted in the usual way on a rod 17 rotatably mounted in the bearings 18, and the paper in the form of a web 16 is carried past the two rollers 19 and 20, the rollers 21 and 22 and under the relieved 25 roller 23, and thence between the rollers 24 and 25; 26 and 27, to the handle and patch attaching devices and over the rollers 28 and 29 to the tuber 30.

During the travel of the web 16 between the 30 rollers 20 and 21, one of its edges is brought into contact with a paste wheel 31 on the shelf 32 which transfers paste from the pot 33 to the edge of the web, which is subsequently used in the tubing to secure the edges of the web together. 35 Also during the travel of the web and before it receives the adhesive and patches, it passes between a knife 158 and a cutting block 159 (see Figure 14) where two longitudinal slits 9 and one transverse slit 8 are cut as shown in Figure 13, 40 or only the transverse slit may be cut by the knife.

The purpose of the slits is to permit the cut-off knife to be relieved or divided to register with these slits when the web is cut off into bag lengths 45 after the handles have been attached, so that the web will only be cut off each side of the slits and the handles will remain projecting from the cut edge, for if the cut-off knife were not relieved, the handles would be cut off from the web with 50 the bag length.

Each of the handles and patch forming and attaching units being the same except of the size and width of the handle it is only deemed necessary to explain one of them in detail, which is 55 as follows.

Each unit is composed of two side frames 15 which are spaced apart in parallel relation and which have secured thereto a water tank 34; a handle former 35; a patch cut-off and a patch 60 and handle transfer device 122; a paste pot 36, and a paster to apply the paste to the traveling web.

The upper part of one of these units is shown in detail in Figure 2; one side 15 being removed 65 and the shafts and rollers and water tank being shown in section for clearness.

The water supply tank 34 has rotatably mounted in its lower end a shaft 38 carrying a roller 39 and a pair of arms 40; the lower ends of the 70 arms 40 carrying a moistening roll 41, relieved in the center and rotating in a water pan 42 which is supplied with water from the tank 34 by a tube 43 and its level maintained by an overflow 44. This moistening roll 41 has a swing- 75

ing movement to and from the patch imparted to it by a roller 45 mounted on one of the arms 40 in rolling contact with a cam 46 secured on the shaft 4.

5 The coating surfaces of this moistening roll 41 also have longitudinal grooves 7, so located in respect to the diameter of the roll 41 and the length of the patch that the dry adhesive 63 on the patch material is not moistened where 10 the cut-off is to take place, as the cut should be in the dry material. The coating surfaces of the roll 41 only come into contact with a portion of the gummed surfaces of the patch material and not in contact with the bare 15 material.

The stock paper material 60 from which the patches are made comprises a roll of narrow paper formed with two rows of spaced apart parallel dry adhesive 63. This patch material 20 60 is mounted on a rod 61 rotatably mounted in the bearings 62 on the frame 15, and this patch material 60 passes under the roller 53 and over and under some of the other rollers to the feeding rollers 50 and 51 which pull the material 25 from the stock roll 60.

The patch material is thus carried to a pair of cut-off rollers 48 and 49, one of which is provided with the usual paper cut-off knife 67 in registry with a slot or pad 5 in the roller 49 30 for severing a patch length from the stock and causing the patch to travel through the rollers 48 and 49 where the end is caught by a pair of spaced pins 125 mounted in the transfer drum 122 and projecting from its raised surface 123 35 and passing through grooves formed in the frame member 70; the patch being impaled upon these pins 125 on the drum 122 which is mounted on the shaft 56, and its diameter being such that its raised surface 123 will support the patch with 40 its moist adhesive surface upward and exposed to receive the handle and retain it until transferred to the web.

The water applying roll 41 is rotated by a gear 64 secured on a shaft 65 which is driven by the 45 gear 66 on the roller shaft 38, which is rotated from the main drive of the machine, and it may here be stated that many of the drives for the different shafts and rollers have not been shown in the drawings for the sake of clearness and as they are of the usual type and do not enter 50 into the invention.

In Figures 4, 5, 8 and 9, the handle former and applicator are shown in detail and comprise a member or bracket 70 mounted on the frames 55 15 and formed with an upper bearing or bearings 71 within which is mounted a rocker-shaft 72, which is rocked by the action of an arm 81 secured to one end thereof and connected by a link 74 in an adjustable manner as at 15 to a 60 rocker-arm 76 which is pivoted to a stud 77 in one of the frames 15; the lower end of this rocker-arm 76 is provided with a roller 78 in rolling contact with a cam 79 secured on a shaft 80 rotatably mounted in the frame 15.

65 To the shaft 72 is also secured an arm 73 to which is pivoted a yoke 82 and a second yoke 83, the purpose of which will be described in detail later.

An arm 151 is secured to the shaft 72 and 70 has secured to its outer end one end of a spring 152 the other end of which is secured to some point on the frame 15, and this spring 152 forces the handle former 111 downward and gives it the power with which to form the handle and

also retains the roller 78 in contact with the cam 79.

The member 70 is provided with the two aligned cord guide tubes 86 and 87 through which the cord for the handles travels; and secured to one 5 side of the frame 15 is a member 88 (see Figures 8 and 9) and upon which are rotatably mounted several transverse shafts which will be explained in detail hereafter; one being a drive shaft 93 which is rotated by a gear 94 in mesh 10 with a gear 95 on the shaft 37 which is in turn driven by a sprocket 97 and chain from a suitable 15 rotating shaft.

Mounted on the shafts 89 and 91 are the cord feed rollers 98 and 99 which are formed with the 15 annular grooves 100 to grip the cord stock 101 and pull it from the stock roll 102; and from these rollers 98 and 99 the cord 101 is fed to the combined feed and cord cut-off rollers 103 and 104 which are mounted on the shafts 91 and 92 and shown 20 in detail in Figure 10 of the drawings; the roller 103 having a cut-off angular knife 105 set therein and registering with a recess or pad 106 in the roller 104; the circumference of the roller 103 being equal to the length of cord required for a 25 handle, and that of the roller 104 being one-half that length; it being understood that in one of the units the handle piece is slightly longer than in the other unit as the finished handles are of 30 different widths so that when attached to the web, they will nest one within the other.

The drive shaft 93 has secured on its forward end a gear 108 which is in mesh with and rotates the two gears 109 and 110 which are secured on the shafts 89 and 91, both being rotated in the 35 same direction as are also the rollers 98 and 103; the rollers 99 and 104 are also gear driven.

The cord 101 is thus fed through the tubes 86 and 87 and over a bridge plate 115 which is 40 slidably mounted in the member 70 and located over the handle die 112 in said member and under the handle former 111 which is attached to the yoke 82 by the rod 114 which gives it vertical movement in the guideways in said member 70.

This bridge plate 115 is for temporarily supporting the handle piece 107 in the die 112 until the former 111 is brought down to force the blank 107 through the die 112 to form the handle; the bridge plate 115 being reciprocated in the member 70 by being pivoted as at 117 to the bell-crank 50 118 which is pivoted as at 119 to the member 70; said bell-crank 118 being pivoted as at 120 to a rod 121 which is connected to the yoke 83 and which has length adjustment, so that as the arm 73 is swung downward as shown in Figure 5, the 55 bridge plate 115 will be receded and the former plate 111 will force the handle blank 107 downward carrying the severed ends thereof free from the tubes 86 and 87.

Mounted below the handle former on a shaft 60 56 is a transfer drum 122 which is provided with a raised surface or portion 123 formed with two parallel annular grooves 124 spaced apart the proper distance to receive the side portions of the handle 107 (the spacing of these grooves upon 65 the two drums being different so that the handles will be of different width and nest when attached to the web) and adjacent to the forward end of the raised portion 123 and in the same are secured the two spurs 125 which engage with and pull the 70 patch 126 from the stock material 60 after it is severed by the knife 67; the patch 126 being supported and carried upon this raised portion 123 with the moistened adhesive upward to receive the formed handle 107 thereon.

Just in advance of this raised portion 123 on the drum 122 are mounted two handle engaging pins 127 which project through the wall of the drum 122, being mounted upon the arms 130 5 which are secured on a shaft 131 which is mounted in the bearings 132 within said drum 122, and to which is imparted a rocking movement by a cam 133 secured to the frame 15, in such a manner that during a portion of the rotation of the drum 122, these pins 127 will project above the surface of 10 the drum and for the remainder of the rotation they will be receded within the drum; they being in their projecting position to engage with the formed handle 107 and carry it from the die and 15 placing it upon the adhesive surface of the patch and transfer both the handle and the patch to the web, after which they recede into the drum, which then moves forward carrying the patch and handle downward between the raised portion 123 20 of the drum 122 and a guide plate 128 which is attached to the member 70 and which is formed to conform to the drum 122 and provided with annular grooves to accommodate the handles 107 25 and the pins 127, thus guiding the passage of the patch and handle from the transfer device to the web.

Referring to Figures 4, 6 and 7; mounted adjacent to the handle former 70 and also upon the frame 15 is a paste pot 36 which is provided with 30 a paste roller 135 rotatably mounted in the lower end thereof on a shaft 136, and below this paste pot 36 in the frame 15 is a shaft 80 upon which is mounted a paste transfer device 138 which has two raised paste applicators 139 in annular relation thereto and two transfer raised applicators 140; the surfaces of all of which are serrated to 35 pick up the paste from the roller 135 and transfer it by contact to the surface of the traveling web as it passes over the roller 141 on the shaft 13; 40 the paste being deposited upon the local surfaces as shown in Figure 7.

The bag web 16 with these gummed surfaces 143 and 144 now travels over the roller 141 in the frame 15, and due to the rate of speed travel of 45 the web and the timing of the rotation of the drum 122, the handle 107 and its patch 126 will be brought into registry with the gummed surfaces 143 and 144 on the web 16 and be deposited thereon where they may be pressed between other 50 rollers to complete their adhesion.

Having thus described my invention, what I claim as new and desire to secure by Letters Patent, is:

1. In a bag making machine of the class described employing a bag forming web, cord handles and reinforcing patches, of means for forming said handles, means for rendering a portion of the surface of said patch adhesive, means for depositing the formed handle thereon, and means 55 for transferring both the formed handle and the patch to and securing the same to the web.

2. In a bag making machine of the class described employing a bag forming web, cord handle material and patch making material, of means 60 for causing the web to travel through the machine, means for forming patches from the patch making material, means for rendering a portion of their surface adhesive, means for forming handles from said cord handle stock, means for 65 combining the handle with the patch, means for coating predetermined local surfaces of said web

with an adhesive, means for bringing the combined handles and patches into contact with said adhesive surfaces and pressing the same together to secure both the handle and the patch to the web, and means for severing a bag length from 5 the web with the handles projecting from the end thereof.

3. In a machine for making handled shopping bags of the class described and employing a web or blank, a cord and a strip of reinforcing material, of means for causing the web to travel through the machine, means for cutting transverse slits in the web, means for forming handles from the cord, means for forming patches from the reinforcing material, means for rendering a 10 portion of the web adhesive adjacent to the slits, means for rendering a portion of the reinforcing patch material adhesive, means for combining the handle and the patch and means for transferring both the handle and the patch to the adhesive 15 portion of the web.

4. In a machine of the class described, the combination with a bag forming web, a handle cord and a reinforcing material, of means for forming slits in the web, means for applying 20 an adhesive to the web adjacent to the slits, means for forming handles from the cord, means for forming patches from the reinforcing material, means for rendering portions of the patches 25 adhesive, means for placing the formed handles upon said adhesive portion of the patch, and means for placing both the patch and handle upon the adhesive portion of the web in such a 30 position that the handles will nest one within the other.

5. In a machine for making handled shopping bags of the class described, comprising means for feeding a bag forming web, means for applying an adhesive upon the web in predetermined local surfaces, comprising a paste pot located above 40 the traveling web, a paste roller mounted therein and rotating in the paste, a cam operated transfer pasting roller adapted to be brought into contact both with the paste roller and the web at 45 intervals during the travel of the web, a cord supply and means for forming handles therefrom, comprising a cord feeding means, a handle length cut-off means and a die for forming the cord into a handle, a patch supply and means for forming the same into patches, means for moistening a 50 portion of the gummed surface of said patches, means supporting and conveying said patches and handles to the gummed portions of the web, and means for severing the web from the stock adjacent to the handle with the handles projecting 55 from the severed edge.

6. In a machine for making handled shopping bags of the class described comprising means for imparting travel to a bag forming web, means for forming slits therein spaced apart, means for applying an adhesive to the web adjacent to the slits, means for forming a pair of cord handles of different widths and lengths, means for forming patches, means for rendering a portion of their surfaces adhesive, means for supporting and 60 moving a pair of said patches, means for placing a pair of the handles upon the patches, and means for securing both of the pair of patches and handles upon the spaced and gummed portions of 65 the web adjacent the slits.

HARFORD K. STEEN.
